W. POTTER

SASH LOCK

Filed July 16, 1925

INVENTOR
William Potter
BY
Howard C. Thompson
ATTORNEY

UNITED STATES PATENT OFFICE.

WILLIAM POTTER, OF NEW YORK, N. Y., ASSIGNOR TO THE POTTER WINDOW-LOCK CORPORATION.

SASH LOCK.

Application filed July 16, 1925. Serial No. 43,897.

This invention relates to window sash locks and particularly to devices of this class for locking both the top and bottom sashes against opening when in closed position or 5 when the windows have been adjusted to predetermined open position; and the object of the invention is to provide a device of the class specified comprising a part adapted to be secured to the top rail of the lower 10 sash of a window and including a spring arm adapted to be placed in engagement with one of the side rails, and a parting strip or bead of the window frame in inclined position for retaining the sashes against 15 opening when said spring arm is set in position; a further object being to provide a device of the class specified, in which the spring arm is movably connected with the part attached to the rail of the bottom sash 20 whereby said arm may be retained in inoperative position when not in use; a further object being to provide the free end portion of the spring arm with a cushioning face to prevent the marring of the window frame 25 and window sash when the device is in use and with these and other objects in view, the invention consists in a device of the class and for the purpose specified, which is simple in construction, efficient in use, and 30 which is constructed as hereinafter described and claimed.

The invention is fully disclosed in the following specification, of which the accompanying drawing forms a part, in which 35 the separate parts of my improvement are designated by suitable reference characters in each of the views, and in which:—

Fig. 1 is a perspective view of a part of a window frame showing parts of the top 40 and bottom sashes with my device mounted in connection therewith and illustrating the method of its use.

Fig. 2 is a plan view of the construction shown in Fig. 1; and

Fig. 3 is a broken section on the line 3—3 of Fig. 2 of the drawing.

In carrying my invention into effect, I provide a plate 5 which is provided at one end portion with a projecting flange or lip 6 and 50 the other end portion of which has a raised or dome part 7, and mounted upon the plate 5 or the dome portion 7 thereof is a disk 8 domed to conform with the dome 7 and to rotate thereon, the disk 8 being riveted or 55 otherwise retained against displacement

from the plate 5 as seen at 9, and such disk is provided at oppositely disposed sides with raised and apertured ears 10.

I also employ a spring arm 11 which is substantially of wish-bone or V-shaped form, 60 and preferably composed of heavy wire fashioned centrally to form one or more spring loops 12, the end portions of which are flared laterally and provided with inwardly projecting and slightly curved ends 65 13 which pass through the apertures of the ears 10 and rest upon the dome portion of the disk 8 as clearly seen in Figs. 1 and 2 of the drawing. The construction of the ends 13 and engagement with the dome portion 70 of the disk 8 is such as to normally hold the free end of the arm 11 in substantially horizontal position with relation to the plane of the plate 5 whereby when the arm is raised when in use, the arm is placed 75 under tension.

Passed through the spring loops 12 is a rivet or other fastening device 14 which serves to retain a cushion facing 15 in position, which facing is U-shaped in form and 80 encircles the outer exposed portion of the loops 12 as clearly seen in Fig. 3 of the drawing. The plate 5 is apertured to receive two or more screws or other attaching devices 16 for mounting the plate 5 in connection with the top rail 17 of the lower sash 18 as seen in Figs. 1 and 2 of the drawing. When the plate 5 is mounted in position, it will be seen that the flange or 85 lip 6 engages the outer face of said top rail 90 whereby the plate is rigidly retained in position and reinforced by the flange or lip which is composed of thin metal and so constructed as to not interfere with the movement of the separate sashes, as will be apparent.

In Figs. 1 and 2 of the drawing, I have also shown part of the top sash 19 and at 20 is shown the parting strip between the separate sashes 18 and 19, and in the use of my improved device the plate 5 is secured to the top rail 17 of the lower sash 18 in such manner that when the arm 11 is raised to bring the free end thereof or the cushion facing 15 in engagement with one of the side rails 21 of the top sash and the face of the parting strip 20, said arm 11 will assume a position substantially forty-five degrees to the horizontal plane of the top rail 17 of the bottom sash. When mounted in this position 105 110

tion, when both sashes 18 and 19 are closed, the raising of the lower sash 18 is prevented as well as the lowering of the top sash, it being apparent that the arm 11 operates in 5 the manner of a wedge and prevents the movement of the separate sashes. It will also be apparent that the arm will function to lock the sashes 18 and 19 when either one or both of the same are in an open position; 10 while it is possible to close either or both sashes when the arm is in operative position, it is impossible to further open the sashes by virtue of the wedge action and lock of said arm 11. The cushion facing 15 prevents the marring of the sashes and parting strip as previously stated, and in addition 15 also provides a better gripping face to prevent slippage and it is preferred that said facing 15 be constructed of leather, rubber or similar strong and durable material.

It will be apparent that when the device is not in use or when it is desired to provide a free opening and closing of the separate sashes, the arm 11 may be moved into the 20 position indicated in dotted lines in Fig. 1, where the said arm rests upon the top of the rail 17 and in longitudinal arrangement with reference thereto. It will also be apparent that the spring loops 12 operate to hold the flaring side members of the arm 11 in engagement with the ears 10 at all 25 times, yet permitting of the attachment and detachment of said arm from the disk 8 whenever desired.

30 It will be understood that while I have shown certain details of construction for carrying my invention into effect, that I am not necessarily limited to these details, and various changes in and modifications of 35 the construction herein shown and described, may be made within the scope of the appended claims without departing from the spirit of my invention or sacrificing its advantages.

40 Having fully described my invention, what I claim as new and desire to secure by Letters Patent, is:—

45 1. A device of the class described comprising a mounting plate, a sheet metal disk rotatably mounted on said plate, an arm carried by said disk and movable into angular positions with reference to said mounting plate, and said arm having spring properties for retaining the same in operative position.

55 2. A device of the class described comprising a mounting plate, a sheet metal disk rotatably mounted on said plate, an arm carried by said disk and movable into angular positions with reference to said mounting plate, said arm having spring properties for retaining the same in operative position, and the free end portion of said arm being fashioned to form a spring loop for retaining said arm in engagement with said disk.

60 3. A device of the class described comprising a plate provided at one end with a flange extending at an angle thereto, the other end portion of said plate being domed, a dome-shaped disk fixedly mounted upon said plate and rotatable on the dome portion thereof, said disk being provided with projecting and apertured ears on oppositely disposed sides thereof, a V-shaped spring arm, the free end portion of which is fashioned to form a spring loop and the other 65 ends of which extend through said apertured ears and rest upon the dome of said disk to give tension to said arm.

70 4. A device of the class described comprising a plate provided at one end with a flange extending at an angle thereto, the other end portion of said plate being domed, a dome-shaped disk fixedly mounted upon said plate and rotatable on the dome portion thereof, said disk being provided with projecting 75 and apertured ears on oppositely disposed sides thereof, a V-shaped spring arm, the free end portion of which is fashioned to form a spring loop and the other ends of which extend through said apertured ears 80 and rest upon the dome of said disk to give tension to said arm, and a cushion facing covering the outer end portion of said arm, and means for retaining said facing in connection with said arm.

85 5. A device of the class described comprising a plate adapted to be secured to a support, a disk fixedly mounted upon and rotatable on said plate, a wedge arm, means for pivotally mounting said arm in connection 90 with said rotatable disk, and means whereby said arm will be placed under tension when raised at an inclination to the horizontal plane of said plate.

95 In testimony that I claim the foregoing as my invention I have signed my name this 14th day of July, 1925.

WILLIAM POTTER.
